UNITED STATES PATENT OFFICE.

MARY A. K. HENDRICKSON, OF LOUP CITY, NEBRASKA.

ENVELOP-SEALER.

1,333,489.

Specification of Letters Patent.

Patented Mar. 9, 1920.

Application filed November 23, 1918. Serial No. 263,918.

To all whom it may concern:

Be it known that I, MARY A. K. HENDRICKSON, a citizen of the United States, residing at Loup City, in the county of Sherman and State of Nebraska, have invented new and useful Improvements in Envelop-Sealers, of which the following is a specification.

This invention relates to devices for facilitating the sealing of envelopes and the principal object of the invention is to provide means whereby the adhesive on the flap may be moistened and means for pressing the moistened flap on the envelop.

The invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:

Figure 1 is a top view of the device;

Fig. 2 is a side view.

In these views 1 indicates the handle and 2 a wire coil secured to said handle and supporting a roller 3. I prefer to make the coil from two pieces of non-rusting wire, one end of each wire passing into the handle as at 4 and the other end, after leaving the coil, being extended and bent at right angles to form a bearing for the roller. As shown, the ends 4 are placed side by side to form a stiff stem for connecting the handle to the coil. The coils extend at right angles, in opposite directions, from the stem and the said coils have their convolutions of gradu-

ally increasing diameters from the stem outwardly. The ends of the wires leave the coils on the same side so that the roller and handle are substantially in the same plane. 45 On the other side of the coils is located a sponge 5 which is secured to said coils by a small piece of wire 6 passing through the sponge and the coils.

When the device is to be used the sponge 50 is saturated with water and then the adhesive on the flap is moistened therefrom, the flap turned over and then the roller run over the flap to firmly stick the adhesive to the envelop.

It is thought from the foregoing description that the advantages and novel features of my invention will be readily apparent.

I desire it to be understood that I may make changes in the construction and in the 60 combination and arrangement of the several parts, provided that such changes fall within the scope of the appended claim.

Having described the invention, what is claimed is:—

A device of the class described comprising a handle, a coiled spring formed of two pieces of wire having their inner ends brought together and extending parallel and engaging the handle, the outer ends of the 70 wire extending in an opposite direction from the other ends and having their extreme ends bent at right angle to form journals, a roller having holes in its ends for receiving said journals, said ends leaving the 75 coils at the same side, a sponge secured to the opposite side of the coil, and a wire passing through the sponge and connected with the coils for holding the sponge to said coils.

In testimony whereof I affix my signature.

MARY A. K. HENDRICKSON.
